(57) **CLAIM**

The ornamental design for a translucent device for smoke evacuation for a laparoscopic procedure, as shown and described.

DESCRIPTION

FIG. 1 is isometric view a translucent device for smoke evacuation for a laparoscopic procedure.

FIG. 2 is a first front view of the translucent device for smoke evacuation for a laparoscopic procedure.

FIG. 3 is the second front view of the translucent device for smoke evacuation for a laparoscopic procedure, turned by 90 degrees compared to FIG. 2.

FIG. 4 is a top view of the translucent device for smoke evacuation for a laparoscopic procedure.

FIG. 5 is a bottom view of the translucent device for smoke evacuation for a laparoscopic procedure.

FIG. 6 is a cross sectional view of the translucent device for smoke evacuation for a laparoscopic procedure; and,

FIG. 7 is an exploded view of the translucent device for smoke evacuation for a laparoscopic procedure.

The broken lines shown in the drawings illustrate portions of the article that form no part of the claimed design.

1 Claim, 5 Drawing Sheets
